AUTOMATIC AIR VALVE

Ferdinand Ziganek, Detroit, Mich.

Application September 1, 1948, Serial No. 47,195

1. Claim. (Cl. 236—66)

1

This invention relates to automatic air valves adapted to be attached to steam radiators and the like and operable by means of a bimetal spring, and the primary object of the invention is to provide a valve of the character indicated comprising the fewest possible parts.

Another object of the invention is to provide a valve of the character indicated above, the component parts of which are adapted to be easily and readily disassembled, easily cleaned and just as easily and readily reassembled.

A further object of the invention is to provide a valve of the character indicated above the outlet of which is arranged so that the hissing and whistling noises commonly occurring in the valves of this kind known and used heretofore are eliminated.

A still further object of the invention is to provide a valve of the character indicated above in which the air passing through said valve imparts a rotating movement to the valve while it moves into closing or opening position toward or away from its seat, whereby a smooth operation of the valve is insured.

An additional object of the invention is to provide a valve of the character indicated above comprising a valve ball supported by a magnetized element preventing all chances of the valve ball to stick in closing position on account of moisture adhering to the valve seat.

The invention resides in the details of construction, and in the combination and arrangement of the several parts of the improved automatic air valve, whereby certain important advantages are attained, as will be hereinafter more fully set forth. It is, however, to be understood that the invention is not to be limited or restricted to the exact construction and combination of parts described in the specification and shown in the drawings, but that such changes and modifications can be made which fall within the scope of the claim appended hereto and definitely pointing out the novel features of the invention.

In the several figures of the accompanying drawings illustrating a preferred embodiment of the invention similar parts are designated by similar reference characters and in order that the invention may be better understood, I will now proceed to describe the same with reference to the accompanying drawings wherein:

Figure 1 is a view in section with parts in elevation of a valve constructed in accordance with an embodiment of the invention;

Figure 2 is an enlarged sectional view taken

2

substantially on the line 2—2 of Figure 1, looking in the direction of the arrows;

Figure 3 is an enlarged sectional view taken substantially on the line 3—3 of Figure 1, looking in the direction of the arrows; and

Figure 4 is a view in perspective of the U-shaped spring.

The automatic air valve as herein embodied comprises a tubular housing 10 having both of its end surfaces finished. The upper end portion of said housing is provided with an internal thread 11 and a cap 12 has on its lower portion an outside thread 13 adapted to engage the internal thread 11. At the upper end of the outside thread 13 an externally projecting circumferential shoulder 14 is formed on the cap 12. An annular gasket 15 preferably made from lead is arranged between the upper end surface of the tubular housing 10 and the shoulder 14 on the cap 12. A plurality of small holes 16 located equidistantly on a circle drawn about the axis of the cap 12 are drilled into said cap from the under side thereof. A valve guide hole 17 is arranged coaxially with the cap 12 and extends upwardly therein from the under side thereof. The diameter of the valve guide hole 17 is such that said hole cuts into the small holes 16 and the guide hole extends slightly deeper into the cap than the small holes. An air outlet hole 18 of a smaller diameter than the guide hole 17 extends coaxially with said guide hole a comparatively short distance upwardly therefrom and communicates with the atmosphere through a hole 19 extending from the outside of the cap 12 at an obtuse angle to the outlet hole 18. The juncture of the outlet hole 18 with the valve guide hole 17 forms the valve seat 20. The wall of the guide hole 17 forms the valve seat 20. The wall of the guide hole 17 and the lower end surface of the cap 12 are carefully lapped to fit the valve body V, which will be described now.

The valve body V is preferably made from stainless steel and comprises a substantially cylindrical plug 21 fitting slidably into the tubular housing 10. A plurality of axially extending, equidistantly spaced grooves 22 are provided in the circumferential surface of the plug 21 and a coaxially arranged valve stem 23 extends upwardly at right angles to the upper surface of said plug 21. The valve stem fits slidably into the guide hole 17. The upper end surface of the valve stem 23 is concaved to receive a valve ball 24 adapted to fit tightly onto the valve seat 20 and to close the air outlet hole 18. An inverted cone 25 is formed on the under side of the valve plug 21 and is arranged coaxially with

said plug. Preferably the apex angle of said cone is a right angle.

The lower end portion of the tubular housing 10 is provided with an internal thread 26 and a plug P has an outwardly threaded upper portion 27 adapted to engage the internal thread 26 in the housing 10. The lower end portion 28 of the plug P has a smaller diameter than the upper portion and extends coaxially downwardly therefrom.

Centrally of the top surface of the upper portion 27 of the plug P a boss 29 is arranged and a comparatively small air hole 30 extends centrally through the entire plug P.

A U-shaped spring 31 is made from bimetal of conventional type and is provided in its bottom element 32 with a hole 32'. The boss 29 extends through this hole and is riveted over to secure the bimetal spring 31 permanently on the plug P. The two arms 33 of said spring extend upwardly into the valve housing 10 and on the upper end portion of each arm a pair of arcuate fingers 34 is formed, and each finger extends laterally from the respective arm 33. The length of the bimetal spring 31 is such, that the valve plug 21 normally rests on the top end surfaces of the arcuate fingers 34, which partly surround the inverted cone 25.

The lower end portion 28 of the plug P threadedly engages one arm of an elbow 35 and a gasket 36 preferably made from lead is arranged about the lower end portion 28 of the plug P and is located between the shoulder 36 formed on said plug by the lower end portion and the upper end surface of the elbow 35. Before the elbow is mounted on the plug P a copper lining 37 is inserted into the counterbored lower portion of the air hole 30. On the lower end of the said lining a conical portion 38 is formed extending partway into the elbow, when the latter is mounted on the plug P. A nipple 39 is fitted into the horizontally arranged arm of the elbow 35 and a copper tubing insert 40 is arranged in the nipple 39 and extends outwardly therefrom.

When the air valve embodied herein has been assembled as described, it is mounted onto a radiator 41 by means of the nipple 39. The copper tubing insert extends into the radiator so that the heat from the radiator is transferred quickly through said insert, the elbow 35, the copper lining 37 and the air hole 30 to the bimetal spring 31. This spring reacts to the heat by urging its arms 33 toward each other so that the fingers 34 engage the inverted cone 25 lifting the valve body V and urging the valve ball 24 into contact with the valve seat 20 closing the air outlet hole 18.

The copper lining facilitates the return of any condensed water in the air hole 30 to the elbow 35. When comparatively cool air rises in the radiator 41 and travels through the elbow 35 and the air hole 30 to the bimetal spring 31, the arms 33 of said spring are urged away from each other permitting the valve body V and the valve ball 24 to drop by gravity downwardly into valve opening position. In order to prevent the valve ball 24 from sticking to the valve seat 20 in consequence of moisture adhering to said seat, the valve body V is magnetized so that the ball 24

is positively moved into valve opening position, when the valve body V moves into such position. The channels formed by the comparatively small holes 16 and arranged about the valve stem 23 permit the air to escape without encountering any obstacle so that the hissing and whistling noises commonly occurring in air valves used heretofore are eliminated.

The air valve proper as embodied herein comprises only four integral parts, namely the housing 10, the cap 12, and the valve body V with the valve ball 24 adhering thereto, and the plug P with the bimetal spring permanently mounted thereon, and these parts are adapted to be disassembled and reassembled easily and readily.

I claim:

In an air valve for radiators, a tubular body 20 interiorly screw-threaded at both ends, a vented plug threaded into the upper end of said body, a counter-bore in the inner end of the vent in said plug, a valve element within said counter-bore, a thermal element within said body, a piston 25 slideable within said body and supported on said thermal element, an axial extension projecting from said piston and engaged in said counter-bore and supporting said valve element in its normally open position, a screw-threaded reducer plug having its larger end threaded into the lower end of said body, an elbow threaded 30 on the smaller end of said reducer plug, and a nipple extending from said elbow for the attachment of the valve assembly to a radiator, said piston having peripheral passageways for the flow of air about the same from within said 35 body to and outward through the said vent past said valve element, said piston being actuated by said thermal element to cause said extension to move said valve element to close said vent by said thermal element when it is activated by the 40 heat of the heating medium admitted to the radiator, the said thermal element being in the form of a U-shaped bimetallic strip and having its lower end portion centrally apertured, arcuate cross members formed at the upper ends of the side portions of said thermal element upon which said piston is seated, a conical portion on the lower side of said piston depending between said arcuate members, said arcuate members being adapted to ride said conical portion to affect a lifting movement to said piston whenever said thermal element is activated to cause the closing of said valve element, and a boss formed on the upper end of said reducer plug about the bore 45 therein and engaged through the said aperture and upset to secure said thermal element in place.

FERDINAND ZIGANEK.
